UNITED STATES PATENT OFFICE.

RALPH C. ERSKINE, OF STAMFORD, CONNECTICUT, ASSIGNOR TO ERSKINE-DANFORTH CORPORATION, A CORPORATION OF NEW YORK.

DESIGN FOR A BEDSTEAD.

Application filed December 1, 1925. Serial No. 15,599. Term of patent 7 years.

To all whom it may concern:

Be it known that I, RALPH C. ERSKINE, a citizen of the United States, residing at Stamford, in the county of Fairfield, State of Connecticut, have invented a new, original, and ornamental Design for Bedsteads, of which the following is a specification, reference being had to the accompanying drawing, forming part thereof.

The figure is a perspective of a bedstead, showing my new design.

I claim:

The ornamental design for a bedstead as shown.

RALPH C. ERSKINE.
